UNITED STATES PATENT OFFICE

HARRY C. MORGAN, OF LAGRANGE, ILLINOIS.

COVER FOR THIRD RAILS.

SPECIFICATION forming part of Letters Patent No. 746,556, dated December 8, 1903.

Application filed May 9, 1903. Serial No. 156,432. (No model.)

To all whom it may concern:

Be it known that I, HARRY C. MORGAN, a citizen of the United States, residing at La-
5 grange, in the county of Cook and State of Illinois, have invented new and useful Im-
provements in Covers for Third Rails, of which the following is a specification.

My invention relates to new and useful im-
10 provements in covers for third rails of elec-
tric-railway systems; and its object is to pro-
vide a device of simple and inexpensive con-
struction, which may be readily placed upon a
15 third rail, so as to prevent persons from
coming into contact therewith.

15 A further object is to so construct the cover
as to permit it to open automatically to en-
able the trolley to travel freely upon the rail.

20 A further object is to provide means where-
by the cover will automatically resume its
normal position over the third rail after the
trolley has passed from therebetween.

25 With the above and other objects in view
the invention consists in providing a cover
which is formed of a series of sections hinged
25 to the ties of the railway at opposite sides of
the third rail, and these sections are of such
size as to contact with each other at their up-
per edges at points directly above the center
30 of the rail. The sections are held in this
closed position by means of springs, which
35 are connected to the hinges thereof. The
ends of the contacting edges of the sections
are cut away or tapered, so that they will be
parted automatically when the trolley comes
35 into contact therewith.

The invention also consists in the further
novel construction and combination of parts
hereinafter more fully described and claimed,
40 and illustrated in the accompanying draw-
ings, showing the preferred form of my in-
vention, and in which—

45 Figure 1 is a side elevation of a portion of
my improved third-rail cover. Fig. 2 is a
plan view thereof; and Fig. 3 is a section on
line $x-x$, Fig. 1.

Referring to the figures by numerals of ref-
erence, 1 is a third rail, mounted in any suit-
able manner upon ties 2 of a railway, and ar-
ranged at suitable intervals upon these ties
50 at opposite sides of the third rail are plates 3,
having ears 4 extending upward therefrom
and within which are arranged pivot-pins 5.

These pins extend through ears 6, projecting
downward from a cover-section 7, which is
L-shaped in cross-section. A spring 8 is 55
mounted upon each pin 5, and one end there-
of engages a cover-section 7, while the other
end bears upon the adjacent plate 3. As the
cover-sections 7 are arranged at opposite
60 sides of the third rail and as said sections
are similar, it is obvious that their upper
edges will normally contact at points directly
within the center of the third rail, and it is
therefore impossible to come into contact
65 with the rail. The ends of the contacting
edges of sections 7 are cut away or tapered,
as shown at 9, and it is therefore obvious that
when the trolley of a car contacts with these
ends 9 of the cover-sections it will force the
70 same apart, thereby tensioning the springs 8. 70
After the trolley has passed from between
two of the sections and into position between
the two adjoining it will be understood that
those sections passed will promptly swing
75 back into their normal or closing positions. 75
It will be seen that this device can be readily
placed in position over third rails located
above ground.

In the foregoing description I have shown
the preferred form of my invention; but I do 80
not limit myself thereto, as I am aware that
modifications may be made therein without
departing from the spirit or sacrificing any of
the advantages thereof; and I therefore re-
serve the right to make such changes as fairly 85
fall within the scope of my invention.

Having thus fully described the invention,
what is claimed as new is—

A cover for third rails consisting of plates
adapted to be secured at opposite sides of a 90
rail and having ears thereon, pivot-pins
mounted in the ears, sections L-shaped in
cross-section pivotally mounted upon the
pins, springs upon the pivot-pins and engag-
ing the plates, and sections whereby the up- 95
per edges of the sections are held normally
in contact, the ends of said edges being cut
away.

In testimony whereof I affix my signature
in presence of two witnesses.

HARRY C. MORGAN.
